CLEANING AND CENTRIFUGING APPARATUS

Hilbert E. Edwards, Mansfield, Ohio, assignor to
Westinghouse Electric Corporation, East Pittsburgh,
Pa., a corporation of Pennsylvania

Application October 9, 1945, Serial No. 621,275

3 Claims. (Cl. 68—12)

1

My invention relates to apparatus for cleaning fabrics and centrifuging cleaning fluid therefrom and has for an object to provide improved apparatus of this kind.

A further object of the invention is to provide improved apparatus of the character set forth having a basket which is accelerated by an electric motor to a relatively high centrifuging speed subsequent to the cleaning of the fabrics, wherein the acceleration of the basket is readily effected even though the voltage of the circuit energizing the motor is below normal.

A further object of the invention is to facilitate acceleration of an electrically driven basket of a washing and centrifuging machine.

These and other objects are effected by my invention as will be apparent from the following description and claims taken in connection with the accompanying drawings, forming a part of this application, in which:

Fig. 1 is a vertical sectional view of a washing and centrifuging machine constructed and arranged in accordance with my invention; and

Fig. 2 is a diagram of the electrical connections for the apparatus shown in Fig. 1.

Referring now to Fig. 1 of the drawing, I have shown my invention applied to a washing machine of the type having a water-containing tub 10 within which a cylindrical basket structure 11 is mounted for rotation about a generally horizontal axis. The front of the tub 10 is provided with an access opening 12 which registers with an access opening 13 formed in the basket 11, and a hinged gasketed door 12a closes the opening 12. The basket 11 is provided with a plurality of vanes 14 for agitating the clothes in the body of wash water during slow speed operation of the basket, as is well understood. The side of the basket 11 is perforate throughout substantially its extent, a few of the perforations being shown at 15. The basket 11 is rotated at high speed in the absence of a body of fluid in the tub 10 for centrifuging cleaning fluid from the fabrics.

The basket 11 is carried by a shaft 16 which is rotatable at low and high speeds by an adjustable two-speed mechanism 17 carried by the end wall of the tub 10. The two-speed mechanism 17 may be constructed in any well-understood manner and has not been shown in detail since mechanisms of this type are well understood in the art. In this connection, a suitable mechanism of this type is disclosed in my Patent No. 2,284,047, granted May 26, 1942. The mechanism 17 is adjusted for high and low speed rotation of the shaft 16 by means of an electromagnet 18, which,

2

when deenergized, provides for low speed operation of the basket 11 and, when energized, effects high speed operation of the basket. The two-speed mechanism 17 is driven by a sheave 19 belted, as shown at 21, to the pulley 22 of an electric motor 23.

Water is admitted to the tub 10 through a conduit 24 under control of an electrically-operated inlet valve 25. The upstream side of the valve 25 is connected to a thermostatically-controlled water mixing valve 26 which is supplied with hot and cold water through conduits 27 and 28. It will be understood that the mixing valve 26 is manually adjustable to provide different temperatures of wash water. A water mixing valve of the type shown at 26 is disclosed and claimed in the patent of Frank Breckenridge, No. 2,296,266, granted September 22, 1942.

Vitiated water is discharged from the tub 10 through a drain conduit 29 by means of a pump 31 driven by the motor 23. Flow of water from the tub 10 to the conduit 29 is controlled by an electrically-operated drain valve 32.

The electric motor 23, the inlet and drain valves 25 and 32, respectively, and the speed-change magnet 18 are energized and deenergized sequentially by means of a timer, generally shown at 33, to provide a predetermined sequence of steps in a washing and centrifuging program. The electrical connections between the timer 33 and the various devices controlled thereby are shown in Fig. 2.

The motor 23 which I have disclosed is of the split phase, squirrel cage type and includes a rotor 35 and main and starting windings 36 and 37, respectively. The main winding is connected to terminals 38 and 39 and is provided with a tap 41 which divides the winding 36 into sections 42 and 43. Accordingly, two running windings or circuits are provided, the first including both sections 42 and 43 in series and the second including the section 42 only. When both sections are energized the motor develops a predetermined torque, and when the section 42 only is energized, the motor provides higher torque due to the reduced impedance of the running winding and higher current therein which produces a stronger rotating field. The motor 23, as explained hereinafter, is operated at high torque during acceleration of the basket 11 in order to reduce the period of acceleration. This feature is particularly desirable where low voltage conditions are encountered. The starting winding 37 is controlled in conventional manner by a centrifugal switch 44 which is open when the speed of

the rotor 35 is above a predetermined value and closed at other times.

The timer 33 includes a relatively small clock type motor 45 for driving, through a speed-reducing mechanism 46, a plurality of cam operating switches by means of a shaft 47. One of the switches is of the double-pole, double-throw type including a first pair of contacts 48 and a second pair of contacts 49 which are selectively bridged by a bridging member 51, the latter being actuated by a cam 52. Energization of the speed change magnet 18 is controlled by a switch 53 operated by a cam 54. Energization of the inlet valve 25 is controlled by a switch 55 operated by a cam 56 and connected in series with a float switch 57 which is open when a predetermined quantity of water is contained within the tub 10 and closed at other times. The float switch 57 is shown in Fig. 1 connected to the lowermost portion of the tub 10. As the construction and operation of float-operated switches of the type shown at 57 are well understood in the art, no further description of the same is deemed necessary. Energization of the discharge valve 32 is controlled by a switch 58 operated by a cam 59. The shaft 47 and the cams carried thereby may be manually advanced by a knob 61 in order to initiate operation of the washing apparatus and to determine the duration of the washing period, as is well understood. The cam shaft 47 is movable at all times in the direction of the arrow in Fig. 2, whether driven by the motor 45 or manually actuated by the handle 61. The source of power for the apparatus is indicated by the line conductors L₁ and L₂.

The apparatus shown in Fig. 2 is in the "off" position wherein all the electrical translating devices are deenergized. In this position, the bridging member 51 is maintained in an "open" position intermediate the pairs of contacts 48 and 49.

In initiating a washing and centrifuging program, the clothes to be washed are deposited in the basket 11 with a suitable detergent and the handle 61 is moved slightly in the direction of the arrow, whereupon the bridging member 51 bridges the contacts 48 and the switch 55 is closed. Accordingly, both sections 42 and 43 of the motor are energized in series by a circuit extending from the line conductor L₁ and including the terminals 38, sections of the winding 42 and 43, terminal 39, one contact 48, bridging member 51, and conductor 62 to the line conductor L₂. The motor, at this time, develops its lower torque which is sufficient to operate the basket at low speed, it being understood that the speed change magnet is deenergized at this time. The timer motor 45 is energized by a circuit including line conductor L₁, timer motor 45, a conductor 45a, the other contact 49, bridging member 51, and line conductor L₂. The closing of the switch 55 by its cam 56 energizes the inlet valve 25 so that water at a temperature determined by the thermostatic valve 28 is admitted to the washer. When the proper amount of water is contained in the tub 10, the float switch 57 is opened for deenergizing the inlet valve 25. The washer now operates for a predetermined period of time, depending upon how far the shaft 47 is advanced manually to complete the washing operation. At the conclusion of the washing operation, the drain valve 32 is opened by the closing of the cam-operated switch 58 so that the vitiated washing fluid is discharged to drain by means of the pump 31.

After the water has been discharged, the high speed solenoid 18 is energized for a period of time, for example, $\frac{3}{4}$ of a minute to 1½ minutes, by the closing of the switch 53. Accordingly, a substantial portion of the water contained in the fabrics is centrifuged therefrom and is discharged by the pump 31. Simultaneously, with the closing of the switch 53, the bridging member 51 is disengaged from the contacts 48 and is moved into engagement with the contacts 49. Accordingly, the section 42 only of the running winding 38 is energized through the tap 41 and, as explained heretofore, the torque of the motor is increased to rapidly accelerate the basket 11 to its centrifuging speed. Operation of the timer motor 45 is continued as the conductor 45a is also connected to one of the contacts 49. The centrifuging, at this time, is of relatively short duration, for example, $\frac{3}{4}$ to 1½ minutes, at the conclusion of which the speed change magnet 18 is deenergized by the opening of the switch 53 and, at the same time, the bridging member 51 is disengaged from the contacts 49 and moved into engagement with the contacts 48 for energizing both sections 42 and 43 of the running winding 38. At the same time, the inlet valve 25 is opened by the closing of the switch 55, it being understood at this time that the float switch 57 is also closed. The water admitted to the tub 10, at this time, is for an agitating rinse which is carried out for a period of about five minutes and at the conclusion of which the drain valve 32 is energized by the closing of the switch 58. Accordingly, the rinse water is discharged from the tub by the pump 31.

After the rinse water is discharged from the tub, the high speed solenoid is again energized by the closing of the switch 53 and the bridging member 51 is moved into engagement with the contacts 48. Accordingly, the motor is again energized through the tap 41 to provide high torque operation. The basket is now accelerated to its high centrifuging speed and is operated at high speed for about five minutes and rinse water is centrifuged from the clothes and discharged by the pump 31. If desired, the motor 23 may be energized through its high torque tap connection 41 throughout the centrifuging period, but preferably the high torque connection is employed only during the period required to accelerate the basket. As shown, the bridging member is shifted from its position in engagement with contacts 49 after about $\frac{3}{4}$ to 1½ minutes' operation at the beginning of the final centrifuging period. At the conclusion of the centrifuging period, the various cams are moved to the position shown in the drawing, wherein all switches are open, the bridging member 51 being moved to its position intermediate its contacts 48 and 49. The apparatus is now inactive, and the cleansed and centrifuged fabrics may be removed from the basket 11.

In the construction of a domestic automatic washer of the type shown herein, I have employed a standard $\frac{1}{4}$ horsepower split-phase washing machine motor frame provided with a running winding tapped to provide high torque operation during acceleration of the basket. I have found that the periods of acceleration of the basket are substantially reduced with a normal potential of 115 volts and that satisfactory acceleration may be accomplished with voltages as low as 95 volts, the temperature rise in the motor being maintained within allowable limits prescribed for a motor for this class of service. My invention

contemplates the use of motors, other than the type shown, arranged, however, for periodic high torque operation.

While I have shown my invention in but one form, it will be obvious to those skilled in the art that it is not so limited, but is susceptible of various changes and modifications without departing from the spirit thereof.

What I claim is:

1. In apparatus for cleaning fabrics and for centrifuging cleaning fluid therefrom, the combination of means for cleaning the fabrics, means for centrifuging cleaning fluid from the fabrics, a motor for driving, alternatively, the cleaning means and the centrifuging means, said motor having first and second circuits energized for effecting, respectively, relatively low and high torque operation of the motor, a control mechanism movable to one station for connecting said cleaning means to the motor, said control mechanism being movable to second and third stations for connecting said centrifuging means to the motor, said centrifuging means being accelerated by the motor when the control mechanism is disposed in its second station and driven by the motor for a centrifuging operation when the control mechanism is disposed in its third station, means controlled by the control mechanism and responsive to movement thereof to said second station for energizing said second circuit and means controlled by the control mechanism and responsive to movement thereof to said first and third stations for energizing said first circuit.

2. In apparatus for cleaning fabrics and for centrifuging cleaning fluid therefrom, the combination of means for cleaning the fabrics, means for centrifuging cleaning fluid from the fabrics, a motor for driving, alternatively, the cleaning means and the centrifuging means, said motor having first and second circuits energized for effecting, respectively, relatively low and high torque operation of the motor, a control member movable to respective stations for sequentially connecting the cleaning means and the centrifug-

ing means to said motor, means responsive to movement of the control member to the station wherein the cleaning means is driven by the motor for energizing said first circuit and means responsive to movement of the control member to the station wherein the centrifuging means is driven by the motor for energizing said second circuit.

3. In apparatus for cleaning fabrics and for centrifuging cleaning fluid therefrom, the combination of a container for a body of cleaning fluid and the fabrics to be treated, a perforate basket arranged within the container for enclosing the fabrics, a two speed transmission for rotating the basket, means for adjusting the transmission for rotation of the basket at relatively low and high speeds for respectively cleaning the fabrics and centrifuging fluid from the fabrics, a motor for driving said mechanism and having first and second windings for respectively providing low and high torque operation of the motor, a timing device controlling said adjusting means to provide alternative operation of the basket at said low and high speeds, and means actuated by the timing device for sequentially effecting energization of the first and second windings, said timing device effecting energization of the first winding during low speed operation of the basket and effecting energization of the second winding for a predetermined period of time when said adjusting means is adjusted for high speed operation of the basket.
